PROTECTIVE ELECTRICAL RECEPTACLE PLATE

Lillian G. Englar, Crestwood, N. Y.

Application December 14, 1934, Serial No. 757,507
Renewed September 9, 1936

4 Claims. (Cl. 247—23)

This invention relates to an improved electric installation wall receptacle plate and more particularly to a type of receptacle plate provided with protective means for automatically closing or covering of the electrical contact apertures in the standard types of electrical outlet fixtures.

Heretofore, the present base receptacles and convenient outlets afford no protection to prevent engaging the live electrical contacts in the present outlet when the receptacle is not in use. It is obvious that it is a simple procedure to insert a foreign piece of conducting material through the exposed openings in the present receptacle plates and obtain a serious injury or burn therefrom. It is well known that such is a common occurrence, especially as a result from tampering with the receptacles by children, that the inflicted injury oft times results in death.

It is therefore a feature of the present invention to overcome the present disadvantages of the receptacle plates and provide protective means to obstruct the apertures through which engagement of the normally live electrical contacts usually is made.

It is a further feature of the invention to lock the protective means obstructing the contact apertures during the period the outlet or receptacle is inoperative, that is not in use.

It is a further feature of the invention to require releasing means or a key to release the protective means to render it operative for use.

It is a further feature of the invention to provide for the protruding prongs of the standard insertable plug as a release key.

It is a further feature of the invention to require a proper setting of the protective means to render the receptacle operative for use.

It is a further feature of the invention to automatically restore itself to its normal or protective position upon removal of the insertable plug.

Further and other features of the present invention will be hereinafter set forth in the accompanying specification and claims and shown in the drawings which by way of illustration is what I now consider to be the best modes in which I have contemplated applying that principle. Other embodiments of the invention employing the same or equivalent principle may be used and structural changes made as desired by those skilled in the art without departing from the present invention and within the spirit of the appended claims.

In the drawings:

Figure 1 is a rear view of the device at an enlarged scale showing the operating mechanism.

Figure 2 is a sectional view taken substantially on line 2—2 of Figure 1.

Figure 3 is a sectional view taken substantially on line 3—3 of Figure 1.

Figure 4 is an elevational view of the device shown in Figures 1, 2 and 3.

Figure 5 is an elevational view of a modified form of the invention.

Figure 6 is an elevational view of a further modified form of the invention in which a door type receptacle plate is employed.

Figure 7 is a detail sectional view of the modified form shown in Figure 5.

Figure 8 is a detail sectional view of the modified form shown in Figure 6.

Figure 9 is an elevational view of a still further modification.

Figure 10 is a detail view in isometric of the locking spring shown in Figure 7.

Referring now to the drawings in which similar parts are designated by the same numerals in the several views, it is believed that a clear understanding of the invention will be had therefrom when considered in conjunction with the following description.

For the sake of clarifying the following description the description of the construction of the invention will be given first, then followed by a description of its operation, and then followed by a description of construction and operation of several modifications of the invention.

General description

Referring now to Figures 1, 2, 3 and 4, the invention is shown comprising a standard rectangular wall receptacle plate 10, of suitable material, preferably insulating material, having a relatively large circular opening 11, and provided with bevelled edges 12 and the regular countersunk screw holes 13 located in the major axis of the plate. An integral part of the plate is shown in Figure 3 to consist of a plate member 14 bridging the circular opening 11 adapted to have a blade spring 15 mounted thereon and guide studs 16 which may be extension portions of the plate 14 or individual studs fastened thereto to retain the spring 15 in position. It is obvious that the member 14 need not necessarily be an integral part of the plate 10, but could be separate therefrom and attached thereto in a convenient manner. Portions of the blade spring 15 near its extremities are bent upwardly as viewed in Fig. 3, the purpose of which will be explained presently.

Superimposed on the plate 10 is a circular disk 17 preferably of insulating material which is suitably fastened to plate member 14 by pin 18 so as to be rotatable. An annular segment 19 with diametrically located recesses 20 is fixedly attached to disk 17. Suitable openings or cutouts 21, preferably oblong shaped to conform to the regular shape of the prongs of electrical insertion plugs, are provided in the disk 17 to per-

mit the ingress and egress of the usual electrical plugs.

The blade spring 15 is adapted to be held in position by pin 18 extending therethrough and normally disposed so that its extremities fit in the recesses 20 in the annular segment 19, thereby maintaining or locking the disk 17 in this position. The oblong openings are located in the disk so that in the locked or normal position they are located over the blade spring as shown in Figure 1, so as to permit the inserted prongs of a plug, for example, to engage portions of the blade spring 15 so that the blade can be depressed by further insertion of the plug prongs to be displaced from the said recesses in the segment 19. A suitable spring 22 disposed about pin 18 is attached to the disk 17 and member 14 to positively return the rotatable disk 17 to its normal position when displaced therefrom.

20

Operation

It was previously mentioned that the openings or cut-outs 21 in the superimposed disk in their normal locked position were located directly above the blade spring 15, which is preferably a width practically equivalent to the length of the openings 21, so that when the prongs of an electric plug or other elements are introduced in the openings the spring will be engaged.

30 It is to be understood that the present plate described is attached to the wall outlets in the same manner as the standard wall flush plate. The electrical contacts in a standard type of wall outlet are disposed along the major axis of the plate 10 as indicated by the dotted section in Fig. 4. The bridged member 14 and spring 15 are disposed along the minor axis of the plate, so that it is obvious that the cut-outs 21 in the disk are normally disposed so that a rotation of the disk 17 through 90° is necessary to align the outlet openings and the openings 21 in the plate 10.

Therefore, it is seen with the disk 17 in its normal locked position the electrical contacts of the wall outlet are isolated in such a manner that conductive elements cannot be introduced thereto, until the disk 17 is unlocked or released and rotated through 90° to align the openings in the disk with the electrical contacts.

It is to be noted that in order to release the disk 17 from its normally locked position the blade spring 15 must be depressed at both of its extremities to clear the recesses 20 before the disk can be rotated. Thus, the insertion of an element in one opening in the disk will not release the disk to permit its rotation.

60 Two elements must be inserted simultaneously to engage the spring 15, for example, the prongs 23 of an electric plug 24. The prongs must be inserted sufficiently to overcome the spring action to displace the extremities of the spring 15 from the recesses in the said segment. This action releases the disk 17 and permits its rotation by the partly inserted prongs of the plug. When rotated through 90° and the openings 21 are aligned with the outlet openings, the prongs of the plug can then be inserted to engage the electrical contacts.

It is understood that the disk 17 is rotated against the action of the fixed spring 22, so that it is obvious upon the egress of the plug prongs from the disk 17, the disk is automatically restored to its normal position to be engaged and locked in this position by the spring 15.

In Figures 5, 7 and 10, a modification of the 75 above principle applied to protective wall plates

is shown comprising two circular disks, a rotatable disk 25 with openings 26 superimposed on the plate 27, and a fixed disk 28 with openings or cut-outs 29 attached to or integral with the plate 27. Both disks to be preferably of insulating material. A suitable pin 29a extending from the disk 25 to disk 28, has attached thereto a U-shaped spring 30 adapted to have its extremities fit into the cut-outs 29 in disk 25 to lock the disk in this position. Insertion of the plug prongs through the 10 openings in disk 25 engage the spring 30 to depress it to the extent that the extremities are forced to release disk 25. When the extremities of the spring are pushed downwardly to release the disk it may be rotated through 90° to align the openings 26 with the cut-outs 29 in disk 28 which are in turn positioned to correspond to the location of the electrical contacts of the outlet box, in this manner permitting contact between the prongs of the plug and contacts of the outlet 20 box. Upon removal of the plug the disk 25 is returned to its normal position by the spring 31 attached to the disks 25 and 28, to be caught and locked by the spring 30.

In Figs. 6 and 8, the principle is applied to the 25 hinged door type of receptacle plate where the openings 32 are provided in the door 33 adapted to be held in a closed position by a cylindrical spring 34. An insulated circular disk 35 with slots 36 adjusted to be positioned directly over the outlet contacts is fixedly attached to the plate 37 and provided with additional slots 38 to permit the arms of the attached spring 39 to pass therethrough. The extremities of the spring arms are bent slightly to be adapted to engage 35 locking studs 40, fixed on the inner surface of the door 33, and in this manner maintaining the door in a locked position. The releasing operation is the same as described hereinbefore, namely upon insertion of the plug the spring arms are displaced from the studs 40 to release the door. When the door is released and opened the plug is permitted to be inserted through the openings 36 to engage the electrical contacts of the outlet. Upon removal of the plug, the door 33 by virtue 45 of its spring 34 is restored to its closed position and locked in the same position by the spring 39 cooperating with studs 40.

In Figure 9 another modification is shown 50 whereby the disk 41 is separate from the plate 42. The plate has embodied therein the circular disk 43 similar to the above described disks with slots 44 corresponding to the location of the electrical contacts to be engaged by the plug and slots 45 permitting the arms of the described U spring 46 55 to extend therethrough so that when the disk 41 is in a lowered position the slots 46 are engaged thereby to lock the disk 41 in this position. The disk is provided with arms 47 adapted to slide through the guides 48 attached to plate 42. The disk 41 is released in the same manner by inserting the prongs of a plug to force the spring arms inwardly as viewed in Fig. 9, to be displaced from the openings 46 thereby permitting the disk to be raised and uncovering the slots 44 adapted to receive the plug prongs for engagement with the electrical contacts. Upon removal of the plug the disk falls by its own weight to automatically cover the contact slots 44 and as is obvious the ends of the U spring engage the slots 46 to hold the disk 70 in a locked position.

It is evident from the description and disclosure of the principle of operation of the device that many modifications of the specific device shown are apparent and suggested so that it is 75

not intended to be limited by the specific illustration of one form of the invention as shown.

It is also obvious that the application of the disclosed device is not limited to a single outlet receptacle but that it can be applied to a multiple outlet type in the same manner as disclosed for a single outlet receptacle. Its application to other forms of outlets is apparent as for example the standard convenient outlets in present day use, 10 that is an outlet device used for extending an electrical circuit to other outlets in desirable positions without interfering with the continuity of the wire.

While there has been shown and described and 15 pointed out the fundamental novel features of the invention as applied to several modifications, it will be understood that various omissions and substitutions and changes in the form and details of the device illustrated and its operation may be 20 made by those skilled in the art without departing from the spirit of the invention. It is the intention, therefore, to be limited only as indicated by the scope of the following claims.

What is claimed is:

25 1. A protective device, as a separate unit to be mounted over electrical outlets; said protective device consisting of a rotatable insulated disc of sufficient size to cover surface area of electrical outlet unit; said disc having plug openings, adapted by a turning movement to be brought into alignment with fixed electrical contact chambers in the usual electric outlet; an axis or pin on which said disc may rotate; yieldable blocking and locking means between said rotatable disc 30 and surface area of electric outlet unit, to definitely lock said disc, said locking means being yieldable only by the pressure of simultaneous insertion of both prongs of a standard electric plug; means to automatically return said rotatable disc into normal locked position when standard electric plug prongs are removed from contact chambers, definitely closing said electric contact chambers when not in use.

2. An insulated outer shell having a superimposed insulated disc, suitably fastened to the back support strip of said outer shell by a pin so as to be rotatable, said disc having plug openings, adapted by a turning movement to be brought into alignment with fixed electrical contact chambers in the usual electrical outlet; a strip of blade spring held in position by said pin between said rotatable disc and a channel-shaped support across the back of said outer shell, in which channel-shaped support said blade spring rests; said blade-spring being shaped so that the two extremities are slightly bent upwards toward the face of said outer shell, fitting into recesses on the back of the superimposed rotatable disc, and holding said disc in locked position when the electrical outlet is not in use; said blade spring being positioned directly under the plug openings in said rotatable disc, so that by pressure of simultaneously inserted prongs of the standard electric plug through said openings in said superimposed disc, said blade spring yields and releases itself from the recesses, and permits the rotation of said disc until the inserted prongs are directly over the electrical contact openings in the usual electrical outlet, permitting complete ingress of plug prongs; a coil spring disposed about the aforementioned pin, one end of said coil spring being fastened to the back support of said insulated outer shell, and the other end to the back of the superimposed disc, said coil spring

tending to return the superimposed rotatable disc to its normal locked position, to definitely close the contact openings in usual electrical outlets when the plug is removed from said electrical outlet.

3. An insulated outer shell, having a superimposed insulated disc suitably fastened to the back support strip of said outer shell by a pin, so as to be rotatable, said disc having plug openings, adapted by a turning movement to be brought into alignment with fixed electrical contact chambers in the usual electrical outlet; a U-shaped locking device adapted to have its extremities fit into the plug openings in the superimposed disc, and thus lock said disc when the outlet is not in use, 15 said U-shaped locking device fitted over the pin connecting the rotatable disc and back support strip of said insulated outer shell, said U-shaped locking device being adapted to yield when the extremities of the plug prongs are simultaneously 20 inserted into openings in said superimposed disc; a coil spring disposed about aforementioned pin, one end of said coil spring being fastened to the back of the superimposed disc, and the other end to the back support of said insulated outer shell, 25 said coil spring tending to return the superimposed rotatable disc to its normal locked position, to close definitely the contact openings in the usual electrical outlet when the plug is removed from said outlet.

4. An insulated outer shell having a superimposed insulated disc, suitably fastened to the back support strip of said outer shell by a pin so as to be rotatable, said disc having plug openings, adapted by a turning movement to be brought into alignment with fixed electrical contact chambers in the usual electrical outlet; a strip of blade spring held in position by said pin between said rotatable disc and a channel-shaped support across the back of said outer shell, in which channel-shaped support said blade spring rests; said blade spring being shaped so that the two extremities are slightly bent upwards toward the face of said outer shell, fitting into recesses on the back of the superimposed rotatable disc, and holding said disc in locked position when the electrical outlet is not in use; said blade spring being positioned directly under the plug openings in said rotatable disc, so that by pressure of simultaneously inserted prongs of the standard 45 electric plug through said openings in said superimposed disc, said blade spring yields and releases itself from the recesses, and permits the rotation of said disc until the inserted prongs are directly over the electrical contact openings in 50 the usual electrical outlet, permitting complete ingress of plug prongs; a coil spring resting in a curved recess in the inner wall of the said outer shell member, positioned so as to permit a turning movement of the said superimposed disc; a lug in the bottom of the said rotatable disc, said lug extending into the said curved recess in the inner wall of the said outer shell member so as to tension the said coil spring when said disc is released for rotation from its locked position by 55 the simultaneous insertion of the plug prongs against the blocking and locking means aforementioned; said coil spring returning the said superimposed rotatable disc to its normal locked position, to definitely close the contact openings in 60 the said electrical outlet, when the plug is removed from said electrical outlet.

LILLIAN G. ENGLAR.
